HEALDS FOR A JET LOOM
Hifumi Saito, Fukuoka-ken, Japan
(14-16 Nakasaji, Harue-cho, Fukui-ken, Japan)
Filed Dec. 14, 1962, Ser. No. 244,786
6 Claims. (Cl. 139—91)

This invention relates to a heald for a jet loom wherein filling yarn is inserted and conveyed in the shed by a stream of fluid such as air or water which is jetted across the loom from a nozzle provided on one side of the loom. It has been proposed that additional nozzles are provided on a lay beam of a jet loom, and air is jetted from the nozzles in the shed through the plane of warp yarns and join with said main stream of fluid to assist transportation of the filling yarn.

The main object of this invention is to provide a heald with eyes which make a clearance in the plane of warp yarns in the vertical direction at the position corresponding to the nozzles for an additional air stream to facilitate jetting of air in the shed and avoiding disturbance of warp yarns.

The invention will be further described with reference to the accompanying drawing, wherein loom parts are not shown as they may be any suitable usual construction and not part of the present invention.

In the accompanying drawing which illustrates a construction of heald and functional parts thereof according to this invention,

FIG. 1 is a vertical sectional view of a heald and a lay beam;

FIG. 2 is a front view of the right hand end of a heald according to this invention;

FIG. 3 is a view similar to that of FIG. 2 of another embodiment of this invention; and

FIG. 4 is a plan view showing the relation between the additional air nozzles and warp yarns when the nozzles are in a position adjacent the warp yarns.

Referring to FIG. 1, 1 designates the plane of warp yarns arranged on a loom, and they make a shed 3 when they are vertically pulled up and down by healds 2 as usual. A nozzle 4 which jets a carrier fluid such as air or water is provided at one side of the loom, abutting against the shed to be made by the warp yarns at the moment when the lay beam is nearly at the most forward position. The nozzle is connected with a high pressure fluid source, and a flexible pipe, not shown, is employed if the nozzle is provided on the lay beam 5 as it reciprocates toward and away from the front of the loom. The incoming end of a filling yarn 6 which has been drawn out from a bobbin, not shown, in a definite length at the time immediately prior to each jet of fluid from the main nozzle 4 is drawn from the nozzle by a jet of carrier fluid.

An air pipe or pipes 7 are mounted on a lay beam 5 and/or reed cap 5a, and are connected to an air pressure source through a flexible pipe or pipes. Each of pipes 7 has one or more nozzles 8 directed in an oblique direction so as to jet an air stream along the direction of the main stream.

The air streams jetted from the additional air nozzles join with the main stream in the shed, and make a long and strong jet sufficient to transport a filling yarn across the loom.

In the pipes which connect the nozzles and their pressure source are provided valves, which control the opening of the pipes in connection with the rocking motion of the lay beam, whereby the fluids are jetted into the shed at the time when filling yarn is to be inserted therein. The incoming end of the filling yarn is quickly transported in the shed by the combined jet, and is beaten by

2

the lay beam 5 at the beat-up position 9 when the filling yarn is tensioned.

In FIG. 2, 10 and 10a denote respectively a pair of bars provided along the upper and lower sides of heald frame 5 for holding the ends of heald wires, and an eye 12 is provided on each wire to guide a warp yarn. A certain number of wires at the position corresponding to the additional air nozzles on the lay beam provides an eye 12a at a little different level from the eyes 12 of other wires, and the wires having an eye at the same level are respectively fixed on the pair of bars 10 and 10a.

In operation of the loom, two healds are pulled in the opposite vertical direction to make a shed 3 in the warp yarns as usual, and the small number of eyes 10a position certain warp yarns at a different level from others so that a vertical clearance 13 is made in the plane of warp yarns as shown in FIGS. 1 and 4. The additional air nozzles are directed into these clearances as shown in FIG. 4 to facilitate jetting of additional air streams.

If there is only one additional air nozzle on the lay beam, all wires on each side of the position corresponding to the air nozzles can be mounted on the heald frame so as to place their eyes at different levels, so that a single vertical clearance is formed at the border.

In an embodiment of the invention shown in FIG. 3, the eye of a number of wires at the corresponding position to the additional air nozzles is elongated as at 14 with the ends of the elongated eyes extending to levels different from those of other eyes, so that a vertical clearance is formed in warp yarns at the position of the long eyes.

In the embodiment shown in FIGS. 2 and 3, two groups of wires are mounted on one heald frame, but each group of wires may be mounted on different frames, and they are piled up and fixed so as to place their eyes at different levels.

I claim:

1. A heald for a jet loom having a nozzle for carrying a weft yarn through the shed in a stream of fluid and having at least one additional nozzle on the beat up means for directing a stream of fluid in the direction of the stream of fluid produced by the weft yarn nozzle, said heald comprising a plurality of heald wires each having an eye therein, the eyes in at least one group of adjacent heald wires which are positioned intermediate the heald wires at the ends of the heald having at least part of the peripheries of the eyes offset in one direction from the eyes in the remainder of the heald wires in the direction of the length of the heald wires, all of the peripheries of the eyes in the group being off-set in the same direction, whereby the warp yarns extending through the eyes in said group of heald wires are lifted out of the plane of the shed to produce an opening in the shed through which the additional nozzle can direct the stream of fluid toward the stream of fluid produced by the weft yarn nozzle.

2. A heald as claimed in claim 1 in which the eyes in said heald wires are substantially round and the eyes in said group of adjacent wires are completely off-set from the eyes in the remainder of heald wires.

3. A heald as claimed in claim 1 in which the eyes in said remainder of heald wires are substantially round, and the eyes in said group of adjacent heald wires are elongated and have part of the peripheries offset from the eyes in the remainder of the heald wires in one direction of the length of the heald wires and have the remainder of the peripheries offset from the eyes in the remainder of the heald wires in the other direction of the length of the heald wires.

4. A heald as claimed in claim 1 in which there are a plurality of groups of adjacent heald wires, the eyes in all of the heald wires being round and the eyes in the groups being offset from the eyes in the remainder of the heald wires in the same direction.

5. In a jet loom having a nozzle for carrying a weft yarn through the shed in a stream of fluid, the combination of a beat up means having at least one additional nozzle thereon for directing a stream of fluid in the direction of the stream of fluid produced by the weft yarn nozzle, and a heald comprising a plurality of heald wires each having an eye therein, the eyes in at least one group of adjacent heald wires which are positioned intermediate the heald wires at the ends of the heald and adjacent the end of said additional nozzle having at least part of the peripheries of the eyes offset in one direction from the peripheries of the eyes in the remainder of the heald wires in the direction of the length of the heald wires, all of the peripheries of the eyes in the group being offset in the same direction, whereby the warp yarns extending through the eyes in said group of heald wires are lifted out of the plane of the shed and the additional nozzle can direct the stream of fluid toward the stream of fluid produced by the weft yarn nozzle through the openings in the shed.

6. The combination as claimed in claim 5 in which the eyes in said heald wires are substantially round and the eyes in said group of adjacent wires are completely offset

from the eyes in the remainder of heald wires, and there are a plurality of at least two additional nozzles, one on the upper part of the beat up means and one on the lower part of the beat up means, the nozzle on the lower part of the beat up means being offset from the nozzle on the upper part of the beat up means in the direction of the weft by a distance equal to the length of the group of adjacent wires and being substantially aligned with the group of adjacent wires in the direction of the length of the wires.

UNITED STATES PATENT OFFICE
CERTIFICATE OF CORRECTION

Patent No. 3,162,215

December 22, 1964

Hifumi Saito

It is hereby certified that error appears in the above numbered patent requiring correction and that the said Letters Patent should read as corrected below.

In the grant, line 3, for "Fukuoka-ken, Japan," read -- Fukui-ken, Japan, --; in the heading to the printed specification, lines 3 and 4, for "Fukuoka-ken, Japan (14-10 Nakasaji, Harue-cho, Fukui-ken, Japan)" read -- 14-10 Nakasaji, Harue-cho, Fukui-ken, Japan --.

Signed and sealed this 10th day of August 1965.
